UNITED STATES PATENT OFFICE.

CHARLES A. CHAPEL, OF EL RENO, OKLAHOMA.

SIGN.

Application filed April 12, 1924. Serial No. 706,064.

To all whom it may concern.:

Be it known that I, CHARLES A. CHAPEL, a citizen of the United States, residing at El Reno, in the county of Canadian and State of Oklahoma, have invented certain new and useful Improvements in a Sign, of which the following is a specification.

The present invention relates to vehicle signals and more particularly to that type of signals which may be imbedded in a highway.

An object of this invention is to provide a signal device which upon erection in a roadway may be collided with or run over by a passing vehicle without damage thereto or impairing its usefulness.

Another object of this invention is to provide a signal which may be permanently fixed in a roadway so as to warn operators of dangerous crossings, prohibited zones or the like.

A further object of this invention is to provide a signal which may be relatively cheaply constructed, having few parts which upon destruction may be easily replaced at small cost.

A still further object of this invention is to provide a signal device which when knocked over or flattened out by colliding with it will automatically right itself into correct signalling position as soon as the pressure or obstruction is removed.

The above and various other objects and advantages of this invention will in part be described in and in part be understood from the following detailed description of the present preferred embodiment, the same being illustrated in the accompanying drawing, wherein:

Fig. 1 is a side elevation of a signal device constructed according to the present invention which is imbedded in a roadway, the portion of the device imbedded in the roadway being shown in section.

Fig. 2 is a view similar to Fig. 1 showing the reverse side of the signal plate.

Fig. 3 is an edge view of the signal showing the tension device for maintaining the signal plate in substantially upright position, the portion of the device imbedded in the roadway being shown in section.

Fig. 4 is a transverse section looking downwardly taken substantially on line 4—4 of Fig. 1, and

Fig. 5 is a fragmentary section of a modified form of the invention.

Referring to the drawing, and first to the form shown in Figs. 1 to 4 inclusive, 10 designates a road, street or other surface over which vehicles are adapted to travel. A casing 11 comprises the base of the sign or signal and is adapted to be imbedded in the roadway 10 as shown in the drawing. The casing 11 has an outwardly extending flange 12 at its lower end providing an anchor to prevent the casing 11 from displacement from or working loose in the roadway 10. The casing 11 is open at its upper end, and seated on the upper edge of the casing across said upper end is a disc or plate 13 of relatively large diameter or width forming the body portion of the sign or signal. Said disc or plate 13 may have suitable legends or indicia on opposite sides for various purposes, such as to warn approaching vehicles of a dangerous crossing, a prohibited zone and the like. The lower edge of the plate 13 fits into the upper side of a supporting head 14 which is preferably of spherical form and which is seated in the upper end of the casing 11 to maintain the plate 13 from shifting laterally from the top of the base or tube 11.

The spherical head 14 permits the rocking of the plate 13 on the upper edge of the tube 11 and holds the edge of the plate from slipping from the tube, and insures the centering of the plate over the tube when the plate is swung into upright position.

Tension means is provided for normally urging the plate or disc 13 into upright position on the base 11. In the present instance this operation is effected by helical spring 18 housed in the tube or base 11, and anchored at one end to the tube and at its other end to the spherical head for normally drawing the lower side thereof into lowermost position and thus support the plate 13 on its edge. The lower end of the spring 18 is anchored to the casing or base 11 by a crossbar 19 riveted or otherwise suitably secured in transverse relation to the lower end portion of the tube 11, and about which is looped the lower extremity 105 of the spring 18. The upper end of the spring 18 is provided with a hook which is engaged through the lower end of a link 15, the upper end of which is slidably received in a slot 16 formed in the spherical head 14 at its lower side and in a plane at right angles to that of the plate 13. A

cross pin or bolt 17 is secured in the head 14 and intersects the slot 16 and pivotally engages the upper end of the link 15 to permit the latter to swing free in the slot when 5 the plate 13 is tilted. The opposite ends of the bolt 17 may be countersunk in the sides of the spherical head 14 so as to prevent outstanding projections or shoulders which would tend to unseat the head 14 or prevent 10 it from turning freely in the upper end of the tube.

The casing 11 is preferably imbedded in concrete in a vertical position, the upper end of the casing being near or flush with the upper 15 surface of the roadway. The spring 18 normally draws the link 15 downwardly and maintains the lower side of the head lowermost to support the plate 13 in a raised position on its lower edge. When a vehicle or 20 other obstacle strikes or runs over the plate 13 the latter is rocked downwardly and lies flat upon the surface of the roadway 10 to permit the vehicle or obstruction to pass over the plate 13 without damaging the 25 same. Immediately the wheels of the vehicle or other obstruction pass over or release the plate 13, the spring 18 draws the plate 13 back into its normal upright position, so that the sign will always be left in its correct 30 indicating position. The ball 16 fits snugly in the upper end of the casing 11 and protects the device in the casing 11 from contact with water, mud, sand, and the like, which would otherwise injure or rust out 35 the parts and impair the free operation of the same.

In the modified form of this invention shown in Fig. 5, 20 designates a plate or disc which is connected to the upper end of 40 the casing 11 and substantially closes the opening in the same. The plate 20 has an upwardly flaring opening 21 through its center for seating a ball or rocker member 22. The ball 22 is secured to the lower edge of the 45 plate 13 and in its lower surface has a slot 16 for hingedly receiving the link 15.

The modified form illustrated is particularly advantageous where the roadbed is not constructed of a solid substance such 50 as concrete. The plate 20 on the upper end of the casing 11 serves as a protecting member, not only keeping out dirt or other substances which might clog the mechanism, but also strengthening the device so that it will 55 be able to withstand the shocks of vehicles riding continuously thereover.

It is of course understood that various changes and modifications may be made in the details of construction and configurations of the above specifically described embodiment of the invention without departing from the spirit thereof, such changes and modifications being restricted only by the scope of the following claims.

What is claimed is:

1. In a vehicle signal device a casing adapted to be embedded vertically in a roadway and having an open upper end, a movable plate having signal legends on its face, normally arranged in vertical edgewise relation across the upper end of the casing, an enlarged spherical head rigid with the lower portion of said plate and fitting partially within the upper end of said casing and closing the upper end of the casing and the lower portion of the head within the casing being provided with a slot extending at right angles to the plane of the plate, a link pivotally mounted in the slot and extending beneath the head, and a spring positioned vertically within said casing and having its lower end anchored in the casing and its upper end loosely connected with the lower end portion of said link, said spring serving to retain the head seated in the upper end of the casing in closing relation thereto and normally maintain said plate in a vertical position.

2. In a vehicle signal device, a casing adapted to be embedded vertically in a roadway and having an open upper end, a plate having signal legends upon its faces, normally arranged in vertical edgewise relation across the upper end of said casing, a spherical head rigid with the lower portion of said plate and fitting partially within the open upper end of said casing, and closing the casing, a link pivotally connected with the lower portion of the head within the casing and having swinging movement at right angles to the plane of said plate and held against turning relative to the head, and a coiled spring positioned vertically within the casing and having its lower end anchored and its upper end terminating in an extension passing through an eye in the lower portion of said link whereby said spring may serve to retain the head seated in the upper end of the casing and yieldably prevent tilting of the plate and rotation of the head.

CHARLES A. CHAPEL.
